CLAIM

The ornamental design for a “USB flash drive,” as shown and described.

DESCRIPTION

FIG. 1 is a top, front, and right side perspective view showing my new design for a USB flash drive, shown without the protective cover for ease of illustration.

FIG. 2 is a front view of the USB flash drive shown in FIG. 1.

FIG. 3 is a rear view of the USB flash drive shown in FIG. 1.

FIG. 4 is a right side view of the USB flash drive shown in FIG. 1.

FIG. 5 is a left side view of the USB flash drive shown in FIG. 1.

FIG. 6 is a top view of the USB flash drive shown in FIG. 1.

FIG. 7 is a bottom view of the USB flash drive shown in FIG. 1; and,

FIG. 8 is front, top, and right side exploded view of the USB flash drive shown in FIG. 1, shown with the USB protective cover.

The dashed lines are for illustrative purposes only and form no part of my claimed design.
